UNITED STATES PATENT OFFICE

FREDERICK A. MANSKE AND WILLIAM M. MCNEIL, OF CHICAGO, ILLINOIS, ASSIGNEES
TO UNITED STATES GYPSUM COMPANY, OF CHICAGO, ILLINOIS, A CORPORATION OF
ILLINOIS

MACHINE FOR FORMING JOINT REINFORCEMENTS

Application filed September 17, 1928. Serial No. 306,582.

This invention relates to a machine for forming joint reinforcement for wall board from wire fabric.

In forming joint reinforcement for plaster-board and wallboard, such as that described in the co-pending application of Charles R. Birdsey and Frederick A. Manske, Serial No. 296,923, filed Aug. 2, 1928, it is desirable to utilize standard electric welded wire fabric which can be purchased on the open market and to cut this fabric into strips of suitable widths and to then bend the free ends of the cut wires into the desired form or shape. It is also desirable that this operation of forming strips of joint reinforcement be carried on automatically so as to reduce the cost of manufacture to a minimum.

An object of this invention, therefore, is to provide a machine for forming strips of joint reinforcement or lacing for plaster and wallboard from rolls of standard, electric welded wire fabric.

Another object of the invention is to provide a machine which is adapted to carry out the above described object automatically, in order to reduce the cost of operation to a minimum; and also to improve machines for forming joint reinforcements in other respects hereinafter specified and claimed.

Reference is to be had to the accompanying drawings forming a part of this specification, in which—

Figure 1 is a side elevation of our improved machine for manufacturing the joint reinforcing strip,

Figure 2 is a plan view of the improved machine,

Figure 3 is a fragmentary, plan view on a large scale showing loop forming mechanism of the machine,

Figure 4 is an elevation of the portion of the machine containing loop forming mechanism shown in Figure 3,

Figure 5 is a fragmentary bottom view of a portion of the bending bars,

Figure 6 is a sectional view through the bending bars taken on the line 6—6 of Figure 5.

Figure 7 is a side elevation of a modified form of machine for cutting the finished

strips of joint reinforcement into desired lengths,

Figure 8 is a plan view of the machine shown in Figure 7,

Figure 9 is a sectional elevation through the machine on the line 9—9 of Figure 8, 55

Figure 10 is a plan view of an intermediate form of the joint reinforcement,

Figure 11 is a plan view of a later intermediate form of the joint reinforcement, and 60

Figure 12 is a plan view of the finished product from our improved machine, namely the joint reinforcement strip.

The electric welded wire fabric sold commercially is usually in the form of rolls 10, and consists of a plurality of longitudinal wires 11, and cross wires 12 welded to said longitudinal wires. These rolls of electric welded fabric may conveniently be 48" wide with the wire spaced 2" longitudinally and transversely but any other dimensions may be used if desired. Our improved machine may be used in connection with an electric welding fabric machine, in which case the electric welded fabric would enter our improved machine directly from the welding machine, rather than being unwound from the rolls 10. Fabric roll 10 is supported on a suitable shaft 13, which is rotatably mounted in an upwardly extending slot bearing 14 formed in a machine framework arm 15. A certain amount of resistance to unwinding is applied to the fabric roll 10 by means of flat springs 16, which are secured on the inner sides of outstanding arms 15, so as to press against the 70 hubs 17 which are clamped onto the roll 10 in any suitable way.

As the wire fabric is unwound from the roll 10, it is desired to cut same into longitudinal strips, each strip having two or more 75 longitudinal wires. For this purpose the wire fabric first passes between upper idler rollers 18 and 19 and corresponding lower idler rollers 20 and 21, these rollers merely serving to steady the wire fabric and direct 80 same into the cutting wheel to be hereinafter described. The means for cutting the cross wires of the wire fabric preferably consists of upper cutting wheels 22 and lower cutting wheels 23, the periphery of said wheels be- 85

90

95

100

ing provided with slots 24 which are spaced apart the same distance on the periphery of the wheel as the distance between the cross wires 12 of the wire fabric.

The upper and lower cutting wheels 22 and 23 are arranged in pairs with the periphery of said wheels overlapping a sufficient distance to cut the cross wires, the said upper and lower wheels being offset and merely separated by a sufficient clearance to obtain the proper cutting action of the cross wires. The upper cutting wheels 22 are secured to a shaft 25, and the lower cutting wheels 23 are secured to a shaft 26, said shafts 25 and 26 being rotatably mounted in suitable bearings 27 and 28 formed in the framework of the machine. The shaft 26 is positively driven with continuous rotation, by means of an electric motor 30 or other suitable source of power, said motor being provided with a suitable speed reducer, not shown, and with a sprocket wheel 31 connected by a chain 32 to a sprocket wheel 33 secured to the shaft 26. The shafts 25 and 26 are geared together so as to rotate at the same speed, by means of an upper gear 34 secured to the shaft 25, and a similar lower gear, not shown, connected to the end of the shaft 26 and meshing with the gear 34. The cutting wheels 22 and 23 are so arranged on the shafts 25 and 26, that the crosswires between every pair of longitudinal wires will be cut so as to leave strips of wire fabric having two or more longitudinal wires connected by the cut pieces of cross wires 12.

It is possible to stop the manufacture of the wire fabric joint reenforcing strips at this point, so as to produce strips with straight outstanding ends as shown in Figure 10, in which case the strips of joint reinforcement will pass over suitable idler rolls 35 and 36 rotatably mounted on the framework of the machine, and then said strips will be wound up to form a roll of strips 37, said roll being supported on a shaft 38 mounted in suitable bearings 39 secured to the framework 40 of the machine. In order to rotate the shaft 38 at the proper speed to allow for the constantly changing diameter of the roll 37 of strips, a jaw clutch half 40 secured to the shaft 38 and a jaw clutch half 41 is rotatably mounted on shaft 38. A sprocket wheel 42 is secured to the clutch half 41 and a spring 43 is arranged between a nut 44, screwed onto the end of shaft 38, and the clutch half 41, said spring tending to urge the clutch half 41 inwardly so that the teeth 45 thereof engage similar teeth on the clutch shaft 40. Thus the clutch half 41 is designed to rotate at a constant speed, while the speed of the clutch half 40 is constantly changing due to the changing diameter of the roll of fabric strips, the teeth 45 of the jaw halves 40 and 41 slipping a sufficient amount to permit the two clutch halves to rotate at different speeds. A

chain 46 connects the sprocket wheel 42 to any suitable source of power such as the motor 30.

Ordinarily, however, it is desirable to bend the cross wire ends 50 rearwardly and inwardly so as to form loops 51 as shown in Figure 12. This desirable but not essential step in the manufacturing process is accomplished after the cutting operation and before the strips are wound on the rolls 37. These loops 51 are formed by means of bending bars 55 and 56 extending above the wire fabric in parallel, abutting relation. One outer end of the bar 56 is provided with a spindle 57, the outer end of such spindle being mounted in a bearing 58 secured to the framework of the machine. The spring 59 extending between the bearing 58 and a washer 60 secured to the bar 56, tends to urge the bar 56 inwardly toward the wire fabric. A similar spindle 61 is secured to the opposite end of bar 55, the outer end of such spindle 61 being received in a bearing 62 formed on the framework of the machine, and a spring 63 on said spindle, tends to urge the bar 55 inwardly toward the wire fabric. The bars 55 and 56 are supported in sliding, parallel and abutting relation, by means of a pair of slide bearings 64 and 65 formed on the framework of the machine.

A strip of metal 66 is secured to the under-face of the bar 56 in any suitable way, as by screws 67, and inwardly extending integral fingers 68 on strip 66 overlap the bar 55, (see Fig. 5). A similar metal strip 69 is secured to the lower face of the bar 55, said strip 69 being provided with integral fingers 70 extending toward and overlapping the bar 56. The fingers 70 and 68 are in alternate arrangement, a lug 71 being formed on the lower surface of each finger 70 and a lug 72 being formed on the lower surface of each finger 68. The centerline of the lugs 71 and 72 is approximately coincident with the abutting surfaces of the bars 55 and 56 and each finger is provided with an outstanding rounded surface 73 which normally lies in the path of travel of the outstanding ends 50 of the cross wire 12 as said cross wires are drawn or pulled along.

In order to cause the continuous forward movement of the wire strips after being severed by the cutting wheels 22 and 23, a drum 75 is positioned below the sliding bars 55 and 56, said drum being provided with radially extending pins 76 arranged in a plurality of annular rows, each row of pins being spaced apart a sufficient distance so that a pair or more of longitudinal wires 11 forming a reinforcing strip, will just be included between said pins. Each pair of pins in a given row is spaced apart on the periphery of the drum 75 a distance equal to the distance between centers of cross wires 12. The drum 75 is secured to a shaft 78 which in turn is rotat-

ably mounted in suitable bearings 79 secured to the framework of the machine. The shaft 78 is driven with a continuous rotary motion by means of a gear 80, or other suitable driving means, secured near one end of said shaft, such gear meshing with an idler pinion 81 which in turn is rotatably mounted on a stud shaft 82 secured in a bearing 83. The idler pinion 81 meshes with a gear 84 which is secured on the shaft 26, so that the shaft 78 is positively driven from the shaft 26.

As seen in Figure 3 when the square backs 85 of lugs 71 and 72 are in abutting relation, the rounded surfaces 73 on such pins are spaced apart from the corresponding drive pin 76 approximately the thickness of the wire used in the cross wires 12, so that as the fabric strips are drawn forward by the drive pins 76, the wire ends 50 are bent rearwardly by engagement with said rounding surfaces 73, to form a wire strip similar to that as shown in Figure 11. It should be understood that the strips may be used in this intermediate form of manufacture, as shown in Figure 11, but it is preferable to bend the wire ends 50 inwardly to form loops 51.

This inward bending of the wire ends 50 to form the loops 51 is accomplished by means of cams 88 and 89, which are preferably in the form of discs secured near opposite ends of the shaft 78. Cam teeth 90 are formed on the outer faces of cams 88 and 89, said teeth being arranged in an annular series, each tooth having a sudden drop 91 and a gradual rise 92. A downwardly extending lug 93 is formed on the lower side of the outer end of bar 56 and a similar downwardly extending lug 94 is formed on the outer end of bar 55, said lugs 93 and 94 lying in the path of travel of the cam teeth 90. The action of the lugs 71 and 72, carried by the cams, as the drum 75 slowly rotates, is for the rounding surface 73 on said lugs to first engage the wire ends 50 and slowly bend them rearwardly, the flat backs 85 of said lugs being in substantially abutting relation as shown in Figure 5 with the lugs 93 and 94 on the high points of cam teeth 90, in which position sufficient clearance is provided to allow the passage of the wire ends 50. The sudden drop 91 on the cam teeth 90 now causes the lugs 71 and 72 to separate under the action of springs 59 and 63 so that said lugs 71 and 72 bend the wire ends 50 inwardly to form loops 51. As the drum 75 then continues to rotate, the pins 76 withdraw from the loops 51 and the bending operation is complete with the fabric in finished form as shown in Figure 12.

For ordinary purposes, it is sufficient to wind the finished strips of wire fabric up into rolls as shown in Fig. 1, but for many purposes it is desired to cut the finished wire reinforcing strips into lengths and for this purpose the modified form of machine is used

as shown in Figures 7, 8 and 9. With this modified type of machine, the finished strips of wire reinforcement, after leaving the drum 75, pass over a substantially horizontal table 96 which is supported on suitable framework 70 which may be in the form of a channel strip 97. To the web of the channel 97 is secured a lower shear knife 98, above which is mounted a movable shear knife 99, the lower cutting edge of shear knife 99 being at a slight angle 75 to the upper edge of the shear knife 98 so that approximately one of the longitudinal wires 11 will be severed at one time as the movable shear knife 99 is moved downwardly by a mechanism to be hereinafter described. The mechanism for intermittently operating the movable shear knife 99 is composed of a shaft 100 mounted in bearings 101 secured to vertical standard 102, an eccentric 103 is secured near each end of the shaft 100, said eccentric 85 being shaped to rotatably receive a circular band 104. A connecting plate 105 is pivotally secured by a connecting rod to the lower side of bands 104, the outer ends of said plate 105 being received in suitable slide ways 106 90 formed in standards 102, the movable shear knife 99 being secured to the lower side of plate 105.

It is desired to have the shaft 100 rotate intermittently through one revolution so as 95 to accomplish a shear cut and so cut off the finished strips of wire reinforcement in lengths of say 48 inches, more or less. For this purpose a clutch is mounted on the shaft 100, one half 108 of such clutch being in the form of a disc secured to the shaft 100. The other half 109 is also in the form of a disc having a cylinder 110 formed around its outer periphery. A hub 111 is formed on the disc 110, said hub being rotatably mounted on the shaft 100. A sprocket wheel 112 is secured to the hub 111 and is connected by chain 113 and suitable gearing not shown to any source of power, such as the motor 30. Internal teeth 114 are formed inside the drum 110 and a semi-circular dog 115 is pivotally mounted on the disc 108 adjacent teeth 114. A lever 116 is secured to the dog 115, and extends substantially radially relative to the disc 108. A spring 117 secured between the dog 115 and 110 a pin 118 formed on the disc 108, normally tends to maintain said dog 115 in engagement with the teeth 114. However, when the lever 116 is actuated by a mechanism to be herein-after described, the dog 115 is rotated into the 115 position shown in Figure 9, so as to be disengaged from the teeth 114 and thus cause the disc 108 and shaft 100 to be disconnected.

In order to engage the lever 116 so that the dog 115 is disconnected from teeth 114, a catch 120 is provided on one end of an arm 121 of a bell-crank lever, said lever being mounted upon a pivot pin 122. The other arm 123 of said lever is connected by a rod 124 to an arm 125 of a bell-crank lever, said 125

lever being pivotally mounted in pivot pin 126. Another arm 127 of said lever carries a weight 128 which normally tends to move the last named bell-crank lever in a counter-clockwise direction. Another arm 129 of said lever is pivotally connected to a bar 130, the opposite end of which is provided with a latch shoulder 131 and a cam surface 132. A shaft 133 is pivotally mounted in bearings 134 and an arm 135 is secured to said shaft, a semi-circular shoe 136 being secured to the outer end of said arm. A pawl 137 is also secured to said shaft, the outer end of said pawl being adapted to engage underneath the bar 130 until said pawl engages shoulder 131 at which time it moves the bar 130 to the right as seen in Figure 9, until the cam surface 132 engages a fixed pin 138 which causes the bar 130 to move upwardly about its pivot until the shoulder 131 disengages from the pawl 137. When the bar 130 is thus released from the pawl 137, the weight 128 causes the catch 120 to again engage the clutch drum 110 to disengage the clutch when one cut has been made.

A semi-circular shoe 136 rocks back and forth as it engages in the underside of the wire fabric. The shaft 133 is normally urged in a counterclockwise direction by means of a lever 140 which carries a slideably mounted weight 141. The outer surface of the shoe 136, frictionally engages the underside of the wire fabric and the surface of said shoe may be roughened to give a better contact if desired. A driven roller 142 is provided above the wire fabric, said roller being secured to a shaft 143 which is mounted in suitable bearings 144 on the framework of the machine. A sprocket wheel 145 is also secured to the shaft 143 and a chain 146 connects said sprocket wheel to a second sprocket wheel not shown secured to a shaft 147. A third sprocket wheel 148 on the shaft 147 is connected by a chain 149 and suitable gearing to any source of power such as the motor 30. A roller 150 is mounted on a shaft 151 directly under the shaft 143, said shaft 151 being retained in slide bearings 152, a suitable spring 153 being also provided to normally urge the roller 150 against the lower face of the wire fabric so that said fabric is firmly but yieldingly gripped between the rollers 142 and 150. After the cut is made by the downward movement of the knife 99, the rapidly driven roller 142 picks up the cut pieces of finished reenforcing strips and quickly moves them forwardly to an inclined surface 155 which takes them to any desired discharge point. The shoe 136 then releases from the cut pieces of wire reenforcement and rotates in a counterclockwise direction under the action of weight 141 to its normal position, this cycle of operations taking place before the drum 110 has made one complete revolution or before the cut has been completed.

In operation, the wire fabric unwinds from the roll of the fabric 10, and passes between upper rollers 18 and 19 and lower rollers 20 and 21 which serve to guide the fabric, and then passes between cutting wheels 22 and 23, where the cross wires between alternate longitudinal wires are cut. The cut strips of fabric then pass to drum 75 which is positively driven and carries driving pins 76 which engage the meshes of the fabric and move same forward with a positive movement. When the fabric strips pass underneath the bars 55 and 56, the cut ends 50 of said cross wires engage rounded surfaces 73 on the lugs 71 and 72 and are bent rearwardly, said lugs 71 and 72 moving together against the action of springs 59 and 63, this action being made positive by means of cam teeth 90 operating on downwardly extending lugs 93 and 94 secured to bars 56 and 55 respectively. After passing the center point, the cam teeth 90 disengage from the lugs 93 and 94 so that the lugs 72 and 73 separate under the action of springs 59 and 63 so as to bend the wire ends inwardly to form wire hooks 51. The continued rotation of the drum 75 then causes the driving pins 76 to disengage from the hooks 51 and the finished fabric strips are wound on roll 37.

In the operation of the modified form of machine shown in Figures 7, 8 and 9, finished fabric strips are cut into desired lengths by means of movable cutting shear 99 operating past a fixed cutting shear 98. The movable shear 99 is operated intermittently by means of clutch halves 108 and 109 which are connected together by pivotally mounted dog 115 engaging the internal teeth 114 at pre-determined intervals. The cut pieces of wire fabric are moved rapidly away from the movable shear 99 by means of rapidly driven roll 142. The shoe 136 bears against the lower face of the wire fabric and operates to move the shaft 133 in a clockwise direction as the cut strip of wire reenforcement moves to the right as shown in Figure 9. This causes the pawl 137 to move along the bar 130 until said pawl engages the catch 131 which operates lever arms 129, 125, rod 124 and lever arms 123 and 121 to cause the catch 120 to release from the lever 116 so that the dog 115 connects the two clutch halves and operates the cutting shears. When the cut pieces of wire reenforcement have passed the shoe 136, the weight 141 returns the shoe to normal position until the time for another cut across the fabric has arrived.

We would state in conclusion that while the illustrated examples constitute certain practical embodiments of our invention, we do not limit ourselves strictly to the details herein illustrated, and described since manifestly the same can be considerably varied without departing from the spirit of the invention as defined in the appended claims.

Having thus described our invention, we claim as new and desire to secure by Letters Patent:—

1. In a machine for forming strips of wire reenforcement, means for supplying wire fabric having longitudinal and cross wires, cutting means adapted to sever such cross wires to form a plurality of strips of wire reenforcement, and means for bending 10 said cut ends of the cross wires to form loops.

2. In a machine for forming strips of wire reenforcement, means for supplying wire fabric having longitudinal and cross wires, means for severing said cross wires 15 to form a plurality of strips of wire reenforcement, means for bending the cut ends of said cross wires at right angles to said longitudinal wires, and means for moving said strips to a discharge point.

3. In a machine for forming strips of wire reenforcement, means for supplying a wire fabric having longitudinal and cross wires, means for severing such cross wires to form outstanding ends, means for bending said 25 ends at substantially right angles to said longitudinal wires, and reciprocating means adapted to further bend such ends inwardly toward the longitudinal wires to form loops.

4. In a machine for forming strips of 30 joint reenforcement, means for supplying wire fabric having longitudinal and cross wires, means for severing said cross wires to form outstanding ends, a rotary element having radially extending pins around the 35 periphery thereof, said pins being adapted to engage said cross wires, and means for continuously driving said rotary elements so as to accomplish the continuous movement of said cut strips.

5. In a machine for forming strips of joint reenforcement, means for supplying a wire fabric having cross wires and longitudinal wires, a pair of cutting wheels in spaced relation and having cutting grooves 45 formed at intervals around the periphery of said wheels, said grooves and said pair of wheels being adapted to register adjacent the cross wires of said fabric so as to sever said cross wires, and means for moving the cut strips of fabric to a discharge point.

6. In a machine for forming strips of joint reenforcement, means for supplying a wire fabric having longitudinal and cross wires, 55 means for cutting said cross wires to form longitudinal strips, the cut ends of said cross wires being in outstanding relation to said longitudinal wires, and reciprocating means having lugs adjacent their lower surface 60 adapted to form said cut wire ends into loops.

7. In a wire strip machine, means for supplying wire fabric having longitudinal and cross wires, means for cutting said cross 65 wires so as to form strips of said fabric, a

plurality of lugs adapted to bend the cut end of said cross wires relative to said longitudinal wires, and cam means adapted to actuate said lugs so that the ends of said cross wires are bent inwardly toward the longitudinal wires to form loops. 70

8. A strip forming machine, means for supplying wire fabric having longitudinal and cross wires, means for severing said cross wires between longitudinal wires, a 75 pair of slidably mounted bars positioned adjacent said strips of material, a plurality of bending lugs associated with each of said bars, and resilient and cam means adapted to control the movement of said bars so that said lugs bend the cut ends of said cross wires so as to form loops. 80
